John J. McCormick INVENTOR.

UNITED STATES PATENT OFFICE.

JOHN J. McCOMISH, OF NEW YORK, N. Y.

CHAIR-SIGNAL FOR THEATERS.

1,133,985.

Specification of Letters Patent. Patented Mar. 30, 1915.

Application filed September 13, 1913. Serial No. 789,696.

To all whom it may concern:

Be it known that I, JOHN J. McCOMISH, a citizen of the United States, residing at 138 West One Hundred and Third street, 5 borough of Manhattan, New York city, in the county and State of New York, have invented a new and useful Chair-Signal for Theaters, of which the following is a specification.

10 The object of my invention is to provide a method whereby the unoccupied chairs in a darkened hall or theater may be quickly and easily located by the attendants, or by persons looking for seats.

15 A secondary object is to provide a means for determining when two such unoccupied chairs are adjacent to each other, in the same row of chairs.

I attain my objects by the devices described in this specification, and illustrated in the accompanying drawings, in which—

20 Figure 1 is a side view of a chair fitted with my invention, the near-side frame of the chair being removed to show the mechanism clearly. Fig. 2 is similar to Fig. 1, except that the working parts are shown in a different position. Fig. 3 is a rear view of two adjacent chairs, fitted with my invention, a portion of each chair frame being 25 removed to give a clear view of the parts. Fig. 4 is an enlarged view of a portion of Fig. 3. Fig. 5 is a diagrammatic view of one of the working parts in various positions, assumed during its operation.

30 Similar parts in the several views are marked by similar letters of reference.

A, A is the chair frame.

B is a vertically swinging seat, such as is commonly fitted to theater chairs, swinging 40 on stud-bearings at a.

C is an actuator in the form of a horizontal lever, pivoted at b to swing in the vertical plane, and having at its outer end an upward extension, c, which terminates in a 45 knob, or button, D. c passes through an opening in the stop-block E, and a helical spring, F, is mounted on c, between D and E, and is normally under compression, holding C in the horizontal position shown in Fig. 1 when the seat, B, is not occupied. C is formed with a downward extension, G, through which there is an oblong slot or opening, d, shown in Figs. 1 and 2.

50 In suitable bearings on the chair-frame there is mounted the rocking shaft, H, which extends the entire length of a row of chairs.

On H, at a point determined by a vertical line dropped midway between two adjacent seats, there is firmly attached the arm, I, which has journalized loosely on its outer, 60 free end, the cross-bar, K. The outer ends of K are entered in the oblong openings, d, d, of the downward extensions G, G, of the levers, C, C, of two adjacent chairs; as shown in Figs. 3 and 4. Operative connection is thus obtained between C and H, through the cross-bar, K, and an arm I. The rocking shaft H, extends an inch or two beyond the end chair of the row, as shown in Fig. 3 and at this point there is attached 65 to H the shutter-arm L, carrying at its outer end the shutter, M, shown in section in Fig. 1, and in full face from the rear in Fig. 3,—the dotted line in Fig. 3 showing the line of section in Fig. 1. M is provided with 70 two windows x and y, fitted with glass of contrasting colors. For descriptive purposes, I shall assume x to be fitted with green glass, and y with red glass.

N is a small electric incandescent lamp, so 75 situated with relation to the shutter, M, that its light will be masked, or uncovered, toward the rear, as M is lowered or raised. N gets its current supply through a switch O. A projecting stud on the free end of O 80 enters into engagement with the lever C at o, as shown in Figs. 1 and 2, and the contacts are arranged to pass current to the lamp N when the seat B is unoccupied, as shown in Fig. 1, and to shut off current when B is 85 occupied, and in the position shown in Fig. 2.

The working of my invention will be easily understood. It will be seen that, in any row of chairs fitted with my device, the 90 two end chairs of the row will each have a single lever C, while each of the intermediate chairs will have two such levers. When all the chairs in a row are occupied, the several seats press downward on their 95 respective buttons D underneath, forcing the working parts into the positions shown in Fig. 2, in which the lamp N, is masked from view toward the rear by the opaque upper part of the shutter, M. The lamp N may 100 be boxed in on all sides excepting the rear, if desired, and, under this condition, when the shutter, M, is dropped to the position shown in Fig. 2, the lamp is entirely hidden from view. To prevent a waste of electric 105 current when it is not needed, I have introduced the switch O in the supply circuit

of the lamp N to shut off the current under the conditions shown in Fig. 2. If there are any unoccupied chairs in a row then the working parts of my new mechanism on such chairs will be in the position shown in Fig. 1, and if any two such unoccupied chairs are adjacent to each other, the cross-bar K, common to such two chairs will be raised to its highest level, operating the arm, I, and through it, the rocking shaft, H, to raise the shutter, M, to the position shown in Fig. 1, when the red-glass window, y, is in line with the lamp N, thus showing the red light to the rear. If, however, there are unoccupied chairs in a row, but no two such unoccupied chairs are adjacent to each other, then any cross-bars affected will be raised at only one end. As a result, the rocking shaft, H, will have an angular movement, sufficient only to raise the shutter, M, to a position midway between its highest, shown in Fig. 1, and its lowest, shown in Fig. 2, and the lamp N, will be in line with the green-glass window, x, thus showing the green light to the rear. An examination of the diagram in Fig. 5 will make this clear. The solid outline marked K¹, may be taken to show the lowest level of the cross-bar, K, corresponding to the conditions when all the seats in a row are occupied. The dotted outline, K², will then show the relative position of K, when two adjacent seats, in the row of chairs are unoccupied; and the inclined dotted outline, K³, will show the intermediate position, when one or more seats are unoccupied, but no two of such unoccupied seats are side by side. It will be seen that either the inclined position K², or the reverse inclined position 40 will produce the same angular movement of the rocking shaft, H.

Having thus shown the operation of my invention as applied to a single row of chairs, it will be evident that, if all the chairs in any hall or theater be equipped with my device, each row having its separate signal lamp showing toward the entrance of the aisle, there will be little difficulty and practically no loss of time in seating those persons who enter while the place is dimly lighted, which is a necessary condition for some forms of entertainment. A glance along the aisle will at once show the place where a vacant seat may be found, as a green light will show at that place, and when two persons are looking for seats side by side, the red light will show where two such seats can be found.

The mechanism and parts, arranged as herein described, show the best form of applying my invention yet devised by me, but I do not confine myself to this form, as such may be variously modified without substantially departing from the spirit of my invention.

I claim as follows:

1. In a chair signal for theaters, the combination with a plurality of seats, of a member extending therealong, a signal shutter operated by the member, a plurality of levers actuated by the chair seats, cross bars intermediate adjacent seats and operated by the levers, and means for transmitting the motion of the cross bars to the member and shutter. 75

2. In a device of the character set forth, the combination with a plurality of seats, of a rocking shaft extending therealong, signal mechanism including a shutter connected to the rocking shaft, an arm connected to the rocking shaft and extending therefrom between adjacent seats, a cross bar loosely journaled on the free end of said arm, and connections between said adjacent seats and said cross bar whereby the occupant of either one seat alone or both seats will cause the signal shutter to be moved to varying distances. 80

3. In a device of the character set forth, the combination of a plurality of seats arranged in a row, a rocking shaft extending therealong, signal mechanism connected to said shaft and including a movable shutter having a plurality of differently colored windows and a lamp adjacent the shutter 95 for selective coöperation with the several windows, actuators arranged adjacent the several seats, means connecting the adjacent actuators and connections between said means and the rocking shaft serving to cause the signal shutter to move a certain distance to indicate one color when a single seat is unoccupied and to a different distance to indicate a different color when two adjacent seats are unoccupied. 100

4. In a device of the character set forth, the combination with a plurality of chairs having movable seats, of a variable signal device, actuators arranged adjacent said seats adapted to be operated thereby when the seats are occupied, each actuator being adapted to be engaged and moved by the seat, means connecting the adjacent actuators and connections between said means and the signal device serving to cause the same to display different indications depending upon whether a single seat is unoccupied or two adjacent seats are unoccupied. 110

5. In a chair signal for theaters, the combination with a movable chair seat, of a lever adapted to be operated in one direction by the seat, said lever having an upward extension c and a downward extension G, a spring associated with the upward extension tending to elevate the lever, a rocking shaft extending along the seat, an arm extending laterally from the shaft, a shutter carried by the rocking shaft, a lamp adjacent the shutter, and means between the 125 130

downward extension G and said arm whereby the indication of the signal will be varied according to the movement of the chair seat.

- 5 6. In a device of the character set forth, the combination with a plurality of seats, of a movable member extending therealong, signal mechanism including a shutter connected to said movable member, an arm connected to the movable member and extending therefrom between adjacent seats, a

cross bar loosely journaled on the free end of said arm, and connections between said adjacent seats and said cross bar whereby the occupancy of either one seat alone or 15 both seats will cause the signal shutter to be moved through said arm and movable member to varying distances.

JOHN J. McCOMISH.
